UNITED STATES PATENT OFFICE

2,530,527

CHEMICAL APPARATUS

Meinhard H. Kotzebue, Houston, Tex., assignor to
Celanese Corporation of America, a corporation
of Delaware

Application July 15, 1947, Serial No. 761,049

6 Claims. (Cl. 23—252)

1
This invention relates to chemical apparatus and relates more particularly to a reaction vessel of improved design adapted to be employed in effecting chemical reactions in the gaseous phase.

An object of this invention is the provision of an improved reaction vessel for use in effecting oxidation reactions in the gaseous phase wherein gaseous hydrocarbons are reacted with oxygen to yield oxygenated products economically and expeditiously.

Another object of this invention is to provide a reaction vessel which is adapted to be employed in effecting hydrocarbon oxidation reactions in the gaseous phase and which enables close control of the oxidation reaction to be maintained.

A further object of this invention is the provision of a reaction vessel wherein all parts are free to expand and contract when the same is employed at elevated reaction temperatures without the use of expansion joints, pipe bends, and the like.

Other objects of this invention will appear from the following detailed description and the accompanying drawing.

In the drawing, wherein a preferred embodiment of my invention is shown,

Fig. 1 is a side-elevational view of my novel reaction vessel, partly broken away to show the inlet headers for the gaseous hydrocarbon and oxygen feed and the outlet for the gaseous reaction products formed.

Fig. 2 is a top plan view of said novel reaction vessel taken along the line 2—2 of Fig. 1, and

Fig. 3 is a sectional view of said novel reaction vessel taken along the line 3—3 of Fig. 1.

Like reference numerals indicate like parts throughout the several views of the drawing.

Referring now to the drawing and more particularly to Fig. 1, the novel reaction vessel of my invention comprises, in the lower portion thereof, an outer cylindrical shell 4 supported upon a base 5 and provided with a hydrocarbon gas inlet header 6 which is fixed thereto by a welded seam 7. Telescopically arranged within shell 4 is a second cylindrical shell 8 of lesser diameter. Shell 4 is joined to shell 8 at an annular shoulder 9, integral with shell 4, welded to shell 8 along a seam 10 and at an annular baffle 11 welded to shells 4 and 8 along seams 12 and 13, respectively. Inner shell 8, between shoulder 9 and annular baffle 11, is provided with a plurality of perforations 14 arranged circumferentially of said shell. The annular space between shoulder 9 and baffle 11 forms a manifold 15 which causes the hydrocarbon gas entering through gas inlet

header 6 and passing through said perforations 14 to be distributed uniformly.

The gas flows through manifold 15 and perforations 14 and passes upward through an annular space 16 defined by the inner surface of shell 8 and the outer surface of an inner tube 17 telescopically arranged within shell 8. Tube 17 is provided with a plurality of circumferentially disposed fins 18 which cover a portion of said tube and extend from the upper end downwardly. Other suitable projections such as spirals, rods, etc. for increasing the heat transfer surface may also be employed. The lower portion of tube 17 is joined to outer shell 8 by a shoulder 19 and a welded seam 19' thus sealing off the base of shell 8. Below seam 19', tube 17 is integral with an elbow 20 welded to shell 4 along a seam 21, said elbow 20 also being integral with a horizontal tube section 21'. A pipe 22, the function of which will be hereinafter described, communicates with elbow 20 and is made integral therewith by a welded seam 23.

The air or oxygen supplied to effect the oxidation reaction enters through a feed pipe 24 provided with a series of perforation 25 at the lower end thereof. Pipe 24 enters shell 8 through a packed gland, generally indicated by reference numeral 26, comprising an annular flange 27 integral with shell 8 and an annulus 28 fitting loosely about pipe 24. Annulus 28 is provided with a plurality of bolt holes (not shown in detail) adapted to receive a plurality of bolts 29 each threaded at the base thereof which register with a series of holes (not shown) suitably formed and tapped in annular flange 27 to receive said bolts. The annular space 30 formed between flange 27 and annulus 28 is provided with a suitable packing (not shown) so that when threaded bolts 29 are taken up a gas-tight fit is obtained.

Pipe 24 is supported by means of a spider, generally indicated by reference numeral 31, comprising a collar 32 welded to pipe 24 and a plurality of symmetrically disposed supporting arms 33. The latter are each provided with flanges 34 which are suitably bolted to vertical supporting members 35 by means of bolts 36 passing through suitable holes (not shown) formed through vertical supporting members 35 and disposed along the length thereof. The lower ends of supporting members 35 are welded to shell 8.

The arrangement described allows feed pipe 24 to be vertically adjusted with respect to tube 17. Thus, when it is desired to change the vertical position of pipe 24 the elements of packed

gland 26 are released by loosening bolts 29, bolts 36 supporting spider 31 are removed and pipe 24 is then shifted up or down, as necessary. After the desired adjustment has been made bolts 36 are replaced so that they register in the holes provided in supporting members 35 at the new level, and bolts 29 in packed gland 26 are then taken up sufficiently to produce the desired gas-tight fit.

When employing my novel reaction vessel for effecting the partial oxidation of hydrocarbons in the gaseous phase, the preheated hydrocarbon feed enters through gas inlet header 6 under pressure and is distributed by manifold 15 so as to pass through circumferential perforations 14 and flow upward through annular space 16 in a substantially even volume. The air or oxygen which is employed to react with the hydrocarbon gas feed enters through pipe 24 and is distributed evenly through perforations 25 at the discharge end thereof. The gaseous hydrocarbon stream and the oxygen or air meet in tube 17 and an exothermic partial oxidation reaction takes place, causing fins 18 on tube 17 to become heated. The heated fins, or other projections, serve to preheat the entering hydrocarbon feed to reaction temperature once the partial oxidation reaction is initiated. This eliminates the necessity of any external preheating of the feed. The oxidation reaction continues as the oxidation products formed pass down tube 17. The oxidation reaction is then halted by quenching the reaction gases to cool the same below reaction temperature by means of a stream of water, or other quench liquid, which is forced in through pipe 22. When water acts as the quench liquid, the product obtained comprises an aqueous solution of oxygenated reaction products, gaseous products and uncondensed gases. The mixture is removed, the oxygenated products separated into their individual components and unreacted oxygen and hydrocarbon recycled to the reactor.

My novel reaction vessel permits very close control of the oxidation reaction to be achieved and, therefore, the degree of oxidation effected due to the fact that the duration of the reaction, for any particular hydrocarbon or mixture of hydrocarbons, may be increased or decreased the desired degree by merely shifting adjustable pipe 24 up or down as the case may be. With pipe 24 in the position shown in Fig. 1 the reaction is of relatively long duration since the reaction will continue down through tube 17 until quenched by the water forced in through pipe 22. With the discharge end of adjustable air inlet pipe 24 close to quench inlet pipe 22, the duration of the reaction will be relatively short since the cooling action of the quench will act to halt the oxidation reaction before it has proceeded very far. Thus, any desired reaction time may be achieved depending upon the type of oxygenated products desired and the necessary duration of the oxidation reaction to form the same.

It is to be understood that the foregoing detailed description is given merely by way of illustration and that many variations may be made therein without departing from the spirit of my invention.

Having described my invention, what I desire to secure by Letters Patent is:

1. In a reaction vessel for effecting chemical reactions, an external shell provided with a plurality of inlets for introducing chemical reactants therein and a discharge tube for removing the reaction products formed, said discharge tube extending a substantial distance within said shell

5 and being spaced therefrom, one of said inlets communicating with the space formed between said shell and said tube and another inlet extending partly within said product discharge tube and its position being adjustable relative to said tube.

2. In a reaction vessel for effecting chemical reactions, a cylindrical external shell provided with a plurality of inlets for introducing chemical reactants therein and a discharge tube for removing the reaction products formed, said discharge tube extending a substantial distance within said shell and being positioned to form an annular space, one of said inlets communicating with the annular space formed between said shell and said tube and another inlet comprising a tube extending partly within said product discharge tube and its position being adjustable relative to said tube.

3. In a reaction vessel for effecting chemical reactions, a cylindrical external shell provided with a plurality of inlets for introducing chemical reactants therein and a discharge tube for removing the reaction products formed, said discharge tube extending a substantial distance within said shell and being positioned to form an annular space, a manifold coextensive with a portion of said annular space and communicating therewith, one of said inlets leading into said manifold, and another inlet comprising a tube extending partly within said product discharge tube and its position being adjustable relative to said tube.

4. In a reaction vessel for effecting chemical reactions, a cylindrical external shell provided with a plurality of inlets for introducing chemical reactants therein and a discharge tube for removing the reaction products formed, said discharge tube extending a substantial distance within said shell and being positioned to form an annular space, a tube leading into the base of said product discharge tube through which a fluid material may be injected into the reaction product discharge stream, a manifold coextensive with a portion of said annular space and communicating therewith, one of said inlets leading into said manifold, and another inlet comprising a tube extending partly within said product discharge tube and its position being adjustable relative to said tube.

5. In a reaction vessel for effecting chemical reactions, a cylindrical external shell provided with a plurality of inlets for introducing chemical reactants therein and a discharge tube for removing the reaction products formed, said discharge tube extending a substantial distance within said shell and being positioned to form an annular space, fins covering portion of the upper part of said discharge tube and projecting into said annular space, a tube leading into the base of said product discharge tube through which a fluid material may be injected into the reaction product discharge stream, a manifold coextensive with a portion of said external shell and annular space and communicating with the latter through perforations in said shell, one of said inlets leading into said manifold and another inlet comprising a tube provided with a plurality of perforations at the discharge end and extending partly within said product discharge tube and its position being adjustable relative to said discharge tube.

6. In a reaction vessel for effecting chemical reactions, a cylindrical external shell provided with a plurality of inlets for introducing

chemical reactants therein and a discharge tube for removing the reaction products formed, said discharge tube extending a substantial distance within said shell and being positioned to form an annular space, fins covering portion of the upper part of said discharge tube and projecting into said annular space, a tube leading into the base of said product discharge tube through which a fluid material may be injected into the reaction product discharge stream, a manifold coextensive with a portion of said external shell and annular space and communicating with the latter through perforations in said shell, one of said inlets leading into said manifold and another inlet comprising a tube provided with a plurality of perforations at the discharge end and extending partly within said product dis-

charge tube, a packed gland integral with the external shell for receiving the last-named inlet tube and means attached to said inlet tube whereby the same may be adjustably positioned relative to said discharge tube.
